UNITED STATES PATENT OFFICE.

PETER G. JACOBSON, OF CHICAGO, ILLINOIS.

DIE MECHANISM.

Application filed July 23, 1924. Serial No. 727,684.

To all whom it may concern:

Be it known that I, PETER G. JACOBSON, a citizen of the United States, residing at Chicago, in the county of Cook and the 5 State of Illinois, have invented a certain new and useful Improvement in Die Mechanism, of which the following is a full, clear, concise, and exact description.

My invention relates to die mechanism 10 and is of particular service in effecting the assembly of the plates of electric condensers with complementary condenser parts. The die mechanism of my invention includes a group of die plates having narrow spaces 15 therebetween in which the condenser plates of a group constituting a condenser side may be partially received preparatory to the die operation. There is another group of die plates complementary to the first and in 20 register therewith, this second group of die plates being moved against the first in the condenser plate assembling operation. Metallic supports are provided for the condenser plates, these supports being slotted 25 to receive the condenser plates, the plate receiving slots being slightly wider than the thickest plate that is apt to be included in the condenser construction. The die plates are desirably formed to swedge the metal 30 of the condenser plate supports between the slots therein so as to contract the width of portions of these slots to hold the condenser plates firmly in assembly with their supports. The swedging effected by the die 35 mechanism produces enlargements, in the metal between the condenser plate receiving slots, that are symmetrical whereby the median planes of the condenser plates are caused to be equidistant irrespective of the 40 thickness of the condenser plates which varies in practice.

The invention will be more fully explained in connection with the accompanying drawing in which Fig. 1 is a plan view 45 of my improved die mechanism; Fig. 2 is a sectional view on line 2—2 of Fig. 1; Fig. 3 is a view somewhat similar to Fig. 2 but showing the two dies in separated relation and a condenser side between the two dies 50 and in the act of being placed in the lower die; Fig. 4 is a sectional view illustrating the lower die with a condenser side held thereby in readiness to be operated upon; Fig. 5 is a sectional view on line 5—5 of Fig. 3 but with the condenser side in place within the lower die; Fig. 6 is a view simi-

lar to Fig. 5 but illustrating the upper die in its lowered position after having effected the swedge; Fig. 7 is a sectional view on line 7—7 of Fig. 4; Fig. 8 is a sectional view on line 8—8 of Fig. 4; Fig. 9 is a perspective view illustrating one of the condenser plate supports and a condenser plate in separated relation; Fig. 10 is a perspective view illustrating one of the condenser supports and a condenser plate after assembly, one condenser plate being omitted from one of the slots to reveal the construction; Fig. 11 is a view illustrating on a larger scale parts of the dies in readiness to complete the 70 assembly of the condenser plates and their support; Fig. 12 is a view similar to Fig. 11 but illustrating the completion of the die operation; Fig. 13 is a sectional view on line 13—13 of Fig. 14; and Fig. 14 is a 75 sectional view on line 14—14 of Fig. 12.

The die mechanism of my invention is particularly adapted to the assembly of the condenser plates of stator condenser sides with the supports for such plates. The 80 stator condenser side illustrated includes a number of condenser plates 1 which are to be assembled with metallic supports 2. These supports are preferably tubular or sleevelike and are initially of U shape as 85 illustrated in Fig. 9. The sides of each support are formed with slots 3 that communicate with the interior of the support to form spaced apart fingers 4. The condenser plates, which are preferably triangular in 90 shape, are placed in the slots 3 whereafter the fingers 4 are curled to finally form a slotted sleeve support as illustrated in Fig. 10 where the tips of the fingers are shown as being spread symmetrically in order to 95 firmly engage the condenser plates and hold the median planes thereof equidistant.

The lower set of die plates 5 are held in upright position upon the base 6. The die plates may be integrally formed with a connecting member 7. The condenser plates are preliminarily held on the pins 9 carried on a mounting 10 which is moved, together with the pins, transversely of the die plates to enable said pins to enter the interiors of 105 the condenser plate supports 2. The supporting block is carried by a cross-head 11 which has pin and slot connection 13 with a lever 13' whereby said cross-head and the block 10 thereon may be moved transversely 110 of the die plates so as to enter the pins 9 into the condenser plate supports 2 prepara-

tory to the assembling operation and to withdraw these pins after the assembling operation to permit the removal of the completed condenser side. The pins 9 are not only passed through the supports 2 but they are also passed through openings 14 in the block 15 and the openings 16 in the block 17, the latter block being movable transversely of the die plates, these blocks 15 and 17 being placed in engagement with the ends of the condenser plate supports 2 to further define the position of the condenser side being operated upon. The die plates 5 are held in assembly with the block 15 by means of the bolts 5'. The block 15 may be held in fixed relation with the base 6 by the bolts 18. An eccentric 19 is received within and engages the sides of the slot 20 in the base extension of the block 17. This eccentric has a handle 21 by which it may be turned upon its shaft 22 to place the block 7 against the adjacent ends of the condenser plate supports 2 to prepare for the die operation, and to withdraw the block 17 from said supports 2 upon the completion of the die operation. The openings 14 and 16 are vertically elongated, the pins 9 being forced against the upper sides of these openings by means of upright coiled springs 23 that are parallel with the die plates and which are bottomed upon the shelf 24 provided upon the cross-head 11 and whose upper ends are received in sockets formed in the bottom of the block 10, this block being adapted to slide vertically upon said cross-head. The springs 23 cause the condenser side being operated upon to be initially held in the upper position illustrated in Fig. 5. The condenser plate support 29 is placed to have its fingers extend downwardly toward the arcuate concave anvils 25 formed in the tops of the die plates 5, while the outer and lower supports 2 are placed to have the fingers thereof extend vertically upward. Unslotted portions of these supports face the concave seats 26 in said die plates.

The upper set of die plates 27 depend from a common base 28 that may be integrally formed therewith, this base being so assembled with the vertically movable carrier 29 that the die plates 27 are in exact register with the die plates 5. When the condenser side to be operated upon is positioned as described and as illustrated in Fig. 5, the upper set of upright die plates 27 is moved downwardly into close proximity to the plates 5 as illustrated in Fig. 6. In this movement the die plates 27 are engaged with portions of the condenser plate supports 2 that are between the condenser plates and press these supports into assembly with the condenser plates. In this downward movement, the anvils 25 curl the fingers of the central and uppermost con-

denser plate support 2 to form this support into a tube whose bore is defined by the uppermost and central pin 9. The upwardly extending fingers of the remaining condenser plate supports are similarly curled by the concave arcuate anvils 30 formed in the bottoms of and near the ends of the die plates 27. The anvils desirably have the convex cross sectional formation illustrated in Figs. 12 and 14 so that the fingers of the condenser plate supports 2 are not only curled as described but are also swedged at their tips and symmetrically, whereby the finger tips are spread into tight-holding engagement with the condenser plates and in a manner to hold the median planes of these plates equidistant. The block 10 is depressed as the curling and swedging operation is in process by means of the adjustable posts 31 depending from the carrier 29 so that the pins 9 are lowered with the supports 2 as the curling and swedging operation is in progress. The pins 9 are thus maintained close to the unslotted portions of the condenser plate supports so that these support portions snugly engage the pins while such portions are in their seats 26, to permit the anvils that are in register with said seats properly to curl the support fingers about the pins.

After the assembly of the condenser plates with their supports has been completed, the lever 13' is moved to withdraw the cross-head 11, together with the block 10 and the pins 9. The handle 21 is also operated to withdraw the block 17. The upper set of die plates being withdrawn, the completely assembled condenser side may be dislodged from the lower set of die plates. To this end, ejecting fingers or blades are placed between the bases of the die plates 5 and are upwardly moved to eject the completed condenser side. The fingers 32 may be hinged, each at one end, and may be provided at their other ends with a common handle 33 whereby the ejecting fingers may be swung upwardly to eject the completed condenser side and downwardly, preparatory to the location of a new condenser side. The bores which are defined by the pins 9 in the supports 2 are generally penetrated by means of assembling bolts which are employed to mount the condenser side in a stationary position. The complementary condenser side is not illustrated. It is customarily rotatively mounted as is well understood in order to adjust the condenser capacity.

Changes may be made without departing from my invention.

Having thus described my invention, I claim:

1. Die mechanism including two sets of die plates with the plates of each set narrowly spaced apart, the plates of one set

mounting and moving it transversely of the sets of dies; and two blocks between which one set of die plates is disposed, one of these blocks being movable transversely of the sets of die plates, and formed with openings receiving said pins.

11. Die mechanism including two sets of die plates with the plates of each set narrowly spaced apart, the plates of one set being in register with the plates of the other; a pin extending transversely of and between the sets of die plates; a mounting for the pin movable toward and from the die plates; spring means pressing upon said

mounting in a direction parallel to the die plates and engageable by an engaging portion provided upon the set of die plates toward which said pin mounting is spring pressed; a cross-head carrying said pin mounting and moving it transversely of the sets of dies; and two blocks between which one set of die plates is disposed, one of these blocks being movable transversely of the sets of die plates, and formed with openings receiving said pins.

In witness whereof, I hereunto subscribe my name.

PETER G. JACOBSON.
